Application June 8, 1939, Serial No. 278,039

5 Claims. (Cl. 179—107)

My invention relates to telephone receivers and particularly to receivers for use in conjunction with hearing aid apparatus of the so-called "bone conduction" type.

In hearing aid apparatus of this type, the sound impulses produced by the receiver are transmitted to the sensory nerves through the bony structure of the head of the user, the sound vibrations being conducted directly to a portion of this bony structure by a vibrating portion of the receiver. Because of this mode of operation, a satisfactory receiver of the bone conduction type must meet a number of very exacting and to some extent conflicting requirements: First, the device must possess high electrical to mechanical efficiency; second, in order that the available output of the receiver can be most efficiently utilized, the mechanical impedance of the vibrating portion of the receiver should match that of the relatively rigid bony structure which it contacts; third, to provide maximum intelligibility, the response characteristic of the receiver should be high over as wide a band of frequencies as is possible; and, fourth, in contrast with these operational requirements, the receiver of necessity must be of relatively small physical dimensions and of light weight.

The receivers previously known to the art have not satisfactorily fulfilled the above enumerated requirements. The inertia type receiver, for example, which is one of the best known prior art devices, has a narrow band or peaked response characteristic and an objectionably low natural period of vibration, due apparently to the rather considerable mass of the vibratory portion of the device. Other types have similar deficiencies.

The principal object of the present invention, therefore, is to provide an improved receiver of the bone conduction type which shall not only fulfill the above stated requirements more satisfactorily than the devices previously known to the art, but which in addition shall be simple in design and inexpensive to manufacture. This object is attained through the provision of a receiver embodying various novel structural features and arrangements, included among which are a novel form of non-metallic diaphragm for engaging the bone structure of the wearer and a novel, yet simple, electro-magnetic actuating means for such diaphragm.

Other objects and the various advantages and novel features of the receiver of my invention will be made more apparent by reference to the accompanying drawings and the following de-

scription of one preferred embodiment thereof. In the drawings—

Figure 1 is a top plan view of a bone conduction receiver embodying the features of the present invention. The cover of the device and a portion of the underlying pole piece structure have been cut away to better illustrate the various structural elements;

Figure 2 is a sectional view on the general line 10 2—2 of Figure 1;

Figures 3 and 4 are sectional views taken respectively on the lines 3—3 and 4—4 of Figure 2;

Figure 5 is a side elevational view illustrating the complete receiver;

Figure 6 is an exploded perspective view of the receiver; and

Figure 7 is a diagrammatic view illustrating the magnetic circuit of the bone conduction receiver of my invention.

The casing of the receiver illustrated in the drawings is made in two parts, a generally flat, more or less rectangularly shaped base portion 11 and a box shaped cover 13 which is adapted to be releasably attached to the base portion 11 by any suitable means, such as the screws 15. Both portions of the casing are preferably made of a molded plastic composition such as the phenolic resin condensates sold under the trade name of "Bakelite," or the like.

The base portion 11 of the receiver, as is shown particularly in Figures 2 and 6, is provided with an annularly shaped recess 17 on its inner side which forms a relatively thin diaphragm 19 located centrally of the base. This diaphragm 19 serves as the vibration conducting member of the receiver, and the outer surface thereof may conveniently be curved inwardly as illustrated in Figures 2 to 5 in order to provide better contact with the bone structure of the user. The edge portions of the base 11 adjacent the diaphragm 19 are relatively thick and unyielding, and serve as a rigid support both for the diaphragm and for the magnet structure of the receiver. The receiver itself is adapted to be held in conventional position on the head of the user by a flexible band 20 adjustably attached to the cover portion 13 of the receiver, as illustrated in Figure 5, or by a suitable handle.

The magnet structure includes a pair of pole pieces 21 and 23 which are preferably made of soft iron. The pole piece 21 is provided with four lugs 25 having countersunk holes 27 drilled therein for receiving screws 29 which serve to fasten the electro-magnetic structure to the base portion 15 of the receiver.

A pair of rectangularly shaped, permanent magnets 31 of suitable high retentivity magnetic material cooperate with the pole pieces 21 and 23 to create magnetic fields of the desired strength in the two air gaps 33 and 34 formed between the cooperating opposed portions 35 of the pole pieces. The two magnets 31 are permanently held in intimate engagement with the side portion of pole pieces 21 and 23 by means of eight clamping screws 37 which engage suitable threaded openings 38 in two cylindrical spacer members 39 of non-magnetic material and a U-shaped combined spacer and bearing support member 41, also of non-magnetic material.

During the assembling of the magnet structure, 15 the U-shaped spacer and bearing support member 41 and the cylindrical spacer members 39 are first attached to the inner pole piece 21. Then, the magnets are put in place, and the outer pole piece 23 is fastened to the members 20 39 and 41. The members 39 and 41 preferably have a length (the dimension A of Figure 6) somewhat less than the corresponding dimension (A' of Figure 6) of the permanent magnets. By virtue of this arrangement, the tightening of the 25 clamping screws 37 draws the cooperating surfaces of the pole pieces 21 and 23 and the permanent magnets 31 into very intimate engagement and assures maximum efficiency in the magnetic circuit. In addition, the positive mechanical interconnecting of the magnets and pole pieces thereby accomplished provides a permanent magnet structure of great strength and rigidity and is to a considerable extent responsible for the great inherent ruggedness of the 35 receiver of my invention.

An armature which comprises an elongated bar-like member 43 of low retentivity magnetic material, preferably soft iron, is pivotally supported adjacent one of its ends on the U-shaped member 41, by means of a suitable pivot pin 42, for movement within the spaced air gaps 33 and 40 34. To minimize friction, it is desirable that the pivot support for the armature shall include jeweled bearings 44, and for most satisfactory results, it appears that the axis of movement of the armature 43 should be located as close to one of the air gaps as is possible.

The armature 43 is adjustably connected to the diaphragm portion 19 of the base 11 by 50 means of a rod-like stylus member 45 which is brazed or otherwise rigidly attached at its inner end to the central portion of the armature. A suitable opening 46 is provided for the stylus in the pole piece 21. As illustrated particularly in Figure 2, the stylus 45 is provided at its outer end with an enlarged threaded portion 47 which is adapted to be engaged by an adjusting nut 49, the inner surface of which bears against a shoulder 50 formed in a metallic insert 51 which is molded integrally with the diaphragm 19. The stylus 45 is locked in place by a suitable threaded locking and sealing disc 53 which engages threads formed in the diaphragm insert 49.

Vibratory movement of the armature 43 and diaphragm 19 in response to microphone voice currents or other energizing means is accomplished by means of two coil windings 55 located in the rectangular space between the magnets 31 and the pole pieces 21 and 23. Each of the windings 55 preferably comprises a large number of turns of very fine copper wire wound on a suitable insulating spool 57. In one satisfactory embodiment of the invention the wind- 70 75

ings 55 each comprised 550 turns of No. 33 enameled copper wire.

The central passageway 58 formed in the insulating spools 55 is made sufficiently large to obviate any possibility of interference with the armature 43 during the operation of the device, and for convenience in positioning and supporting the windings 55, it is desirable that the end portions of the spools shall be square with an area substantially equal to the cross sectional area of the space between the magnets and the pole pieces. The windings 55 are connected in series, and the ends of the interconnected windings are in turn connected to socket type connectors 59 molded into an upstanding portion 61 of the base 11.

The magnetic circuit and the mode of operation of the receiver may best be understood by reference to Figure 7, wherein the ring 31a is representative of the two permanent magnets 31. As will be seen by reference to that figure, the magnetic field across both of the spaced air gaps 33 and 34 is in the same direction. By virtue of this, the reaction forces between the air gap fields and the field created in the movable armature 43 in response to the flow of voice currents set up in the windings 55 by the microphone 63 and battery 65, or other energizing means, will cause rotation of the armature and corresponding movement of the diaphragm 19. Moreover, any rotative movement of the armature 43 away from its normal central position in the air gaps will tend to increase the reaction force producing such movement by providing a path of progressively decreasing reluctance through the right hand portion 35 of one pole piece, through the armature, and thence through the left hand portion 35 of the other pole piece. This effect intensifies the response of the armature to its energizing currents and produces a much more sensitive instrument than any of the prior known devices.

The structural features and arrangement of the armature 43, and the associated magnet structure and diaphragm 19, constitute the most important features of the present invention. For best results in the ordinary types of deafness, a bone conduction type hearing aid receiver should have a mechanical resonant frequency at about 1800 cycles per second, and the receiver should provide substantial uniform response (within 10 or 15 decibels) over the range from 500 to 3500 or 4000 cycles per second.

The prior art bone conduction type receivers, 55 in part due to the relatively great weight of the vibratory portion thereof (10 to 12 grams in practical units), have a maximum mechanical resonant frequency at about 1000 to 1500 cycles per second, and what is more serious, have a rather 60 sharply peaked response characteristic (resulting in the output being down at least 20 decibels at a frequency of 2000 cycles per second, and greater still for higher frequencies). The structural arrangement of the present invention, however, makes possible a receiver wherein the total weight of the vibratory portion thereof is within the range of $\frac{1}{2}$ to 4 grams, with the result that mechanical resonant frequencies of the order of 1800 cycles per second are readily attainable. Moreover, the relatively light weight vibratory portion of the receiver of the present invention provides a much more uniform and much higher response characteristic over the entire range of 500 to 4000 cycles than has ever been attained heretofore; output substantially uniform as be-

fore prescribed can be obtained. Under standard manufacturing practices, it is preferred that the total weight of the vibratory portion of the receiver of my invention shall be within the range of $1\frac{1}{2}$ to 2 grams.

In addition to the increased frequency of mechanical resonance and the more uniform response characteristic made possible by the improved armature and magnet structure of the present invention, a further desirable characteristic results from the fact that the mechanical resonant frequency of the receiver can be readily changed by merely changing the thickness of the diaphragm portion 19. This is most important in the provision of hearing aid apparatus for deaf persons whose hearing is not uniformly impaired over the total band of audible frequencies. In many such instances, the utilization of a receiver which is mechanically resonant, and hence yields its maximum output in that portion of the frequency band where the hearing is most impaired, will make it possible for the user to distinguish sounds much more clearly than is possible with standard frequency receivers. Heretofore, however, the excessive cost of manufacturing a line of receivers resonant at various non-standard frequencies has almost precluded the use of anything but standard frequency apparatus. This present invention fully remedies this situation, since a complete line of receivers resonant at various other than standard frequencies can be supplied by the use of one standard mechanism and a series of base portions 11 having diaphragms of different thicknesses.

Tests have shown that a hearing aid receiver of the type disclosed herein may be used as a microphone with very satisfactory results, the receiver when so used being held in contact with the throat of the wearer by a suitable band or clamp. While the efficiency is somewhat less than that of the more conventional forms of microphone, the receiver when so used has particular application in places where the surrounding noise level is extremely high, as for example, in an airplane or in the broadcasting of sports events. In these instances the microphone will pick up very little, if any, of the surrounding noise, although by suitable amplification it will clearly transmit the sound vibrations of the voice of the wearer.

In the foregoing I have disclosed the features of an improved bone conduction type receiver. The receiver of my invention utilizes a novel vibratory system of a type very different from any previously known to the art, and in addition it utilizes a novel electro-magnetic system for operating this vibratory means. It will be evident to those skilled in the art that various devices may be developed utilizing the principles which I have disclosed in the foregoing. Accordingly, it is my desire that the accompanying claims shall be accorded the broadest possible construction consistent with the language appearing therein and the prior art.

I claim the following as my invention:

1. In a receiver of the class described, a casing which includes a plate member of non-magnetic material having relatively rigid edge portions and a centrally located, relatively flexible diaphragm portion which constitutes the vibratory element of said receiver for contacting a portion of the bony structure of the user of said receiver, and means located within said casing for actuating said vibratory element, said last

5 mentioned means comprising a stationary permanent magnet structure which is fixedly attached to the rigid edge portions of said plate member and which includes cooperating pole pieces for creating two separate magnetic fields spaced some distance from each other, an armature comprising an elongated bar member of magnetic material pivotally supported upon a stationary support means which is fixedly attached to the rigid edge portions of said plate member, said armature having a portion located within each of said spaced magnetic fields, and means mechanically connecting said armature to the diaphragm portion of said plate member.

10 2. In a receiver for use in conjunction with bone conduction hearing aid apparatus and the like, in combination; a plate member of non-magnetic, molded material, having an annularly shaped recess for providing a relatively flexible diaphragm portion which constitutes the vibratory element of said receiver, the edge portions of said plate member adjacent said diaphragm portion being relatively rigid; a first pole piece in the form of a thin plate member, with diametrically disposed inwardly-turned sections, secured flatwise to said relatively rigid edge portions; a second pole piece in the form of a thin plate member with diametrically disposed inwardly-turned sections; means for mounting said second pole piece in spaced relationship with said first pole piece so as to bring said diametrically disposed inwardly-turned sections of the second pole piece into spaced registration with the corresponding diametrically disposed inwardly-turned sections of said first pole piece to thereby provide a pair of diametrically spaced air gaps therebetween; a pair of permanent magnets secured between opposite sides of said pole pieces; said pole pieces and permanent magnets included therebetween providing a permanent magnet housing structure with spaced apart magnetic fields in said air gaps between each pair of said registering spaced apart inwardly-turned sections; an armature extending between said spaced apart magnetic fields; armature support means; bearing means for pivotally mounting said armature adjacent to one end thereof in said armature support means; and adjustable means operatively connecting said armature at a point in between said spaced apart magnetic fields to the center of said annular diaphragm portion.

15 3. In a receiver for use in conjunction with bone conduction hearing aid apparatus and the like, in combination; a generally rectangularly shaped plate member of non-magnetic, molded material, having a centrally located annularly shaped recess for providing a relatively flexible diaphragm portion which constitutes the vibratory element of said receiver, the edge portions of said plate member adjacent said diaphragm portion being relatively rigid; a first pole piece in the form of a generally rectangularly shaped thin plate member secured flatwise to said relatively rigid edge portions and covering said diaphragm portion; pole extensions inwardly-turned from the opposite ends of said first pole piece; a second pole piece in the form of a thin generally rectangularly shaped thin plate member; pole extensions inwardly-turned from the opposite ends of said second pole piece; means for mounting said second pole piece in substantially parallel spaced relationship with said first pole piece so as to bring said pole extensions into spaced apart register to provide a pair of air gaps between the ends of said pole pieces; a pair of gen-

erally rectangularly shaped permanent magnets clamped between opposite sides of said pole pieces; said pole pieces and permanent magnets clamped therebetween providing a permanent magnet box-shaped housing structure with magnetic fields at the opposite ends thereof between said registering spaced apart pole extensions; a bar-shaped armature extending between said magnetic fields; a U-shaped support member secured to said first pole piece and disposed in one end of said box-shaped housing structure; bearing means for pivotally mounting said armature adjacent one end thereof between the arms of said U-shaped support member; and adjustable means operatively connecting said armature at a point in between said spaced apart magnetic fields to the center of said annular diaphragm portion; the distance between said magnetic fields and the length of said armature both being at least as great as the outside diameter of said annular diaphragm portion.

4. In a receiver for use in conjunction with bone conduction hearing aid apparatus and the like, in combination; a plate member of non-magnetic, molded material, having an annularly shaped recess for providing a relatively flexible diaphragm portion which constitutes the vibratory element of said receiver, the edge portions of said plate member adjacent said diaphragm portion being relatively rigid; a first pole piece in the form of a thin plate member, with diametrically disposed inwardly-turned sections, secured flatwise to said relatively rigid edge portions; a second pole piece in the form of a thin plate member with diametrically disposed inwardly-turned sections; means for mounting said second pole piece in spaced relationship with said first pole piece so as to bring said diametrically disposed inwardly-turned sections of the second pole piece into spaced registration with the corresponding diametrically disposed inwardly-turned sections of said first pole piece to thereby provide a pair of diametrically spaced air gaps therebetween; a pair of permanent magnets secured between opposite sides of said pole pieces; said pole pieces and permanent magnets included therebetween providing a permanent magnet housing structure with spaced apart magnetic fields in said air gaps between each pair of said registering spaced apart inwardly-turned sections; an armature extending between said spaced apart magnetic fields; armature support means secured to said first pole piece; bearing means for pivotally mounting said armature adjacent to one end thereof in said armature support means; a longitudinally split winding disposed within said permanent magnet housing structure and surrounding said armature for energizing the same;

and adjustable means passing through the split section of said winding and mechanically connecting said armature at a point in between said spaced apart magnetic fields with the center of 5 said diaphragm portion.

5. In a receiver for use in conjunction with bone conduction hearing aid apparatus and the like, in combination; a generally rectangularly shaped plate member of non-magnetic, molded 10 material, having a centrally located, annularly shaped recess for providing a relatively flexible diaphragm portion which constitutes the vibratory element of said receiver, the edge portions of said plate member adjacent said diaphragm portion being relatively rigid; a first pole piece in the form of a generally rectangularly shaped thin plate member secured flatwise to said relatively rigid edge portions and covering said diaphragm portion; pole extensions inwardly-turned 15 from the opposite ends of said first pole piece; a second pole piece in the form of a generally rectangularly shaped thin plate member; pole extensions inwardly-turned from the opposite ends of said second pole piece; means for mounting said second pole piece in substantially parallel spaced relationship with said first pole piece so as to bring said pole extensions into spaced apart register to provide a pair of air gaps between the ends of said pole pieces; a pair of generally rectangularly shaped permanent magnets 20 clamped between opposite sides of said pole pieces; said pole pieces and permanent magnets clamped therebetween providing a permanent magnet box-shaped housing structure with magnetic fields at the opposite ends thereof between said registering spaced apart pole extensions; a bar-shaped armature extending between said magnetic fields; a U-shaped support member secured to said first pole piece and disposed in one 25 end of said box-shaped housing structure; jewelled bearing means for pivotally mounting said armature adjacent one end thereof between the arms of said U-shaped support member; a pair of co-axially spaced apart windings connected in series circuit relationship wound on rectangularly shaped spools disposed within said permanent magnet box-shaped structure and surrounding said armature for energizing the same; and adjustable means passing through the space between said windings and mechanically interconnecting said armature at a point in between said spaced apart magnetic fields to the center of said diaphragm portion; the distance between said spaced apart magnetic fields and the length 30 of said armature both being substantially equal to the outside diameter of said annular diaphragm portion.

PAUL A. BOTTORFF.
